UNITED STATES PATENT OFFICE.

EDMOND N. BOURDON, OF CHICAGO, ILLINOIS.

ICE-CREAM CABINET.

Application filed December 10, 1921. Serial No. 521,432.

To all whom it may concern:

Be it known that I, EDMOND N. BOURDON, a citizen of the United States, and a resident of the city of Chicago, county of Cook, and 5 State of Illinois, have invented certain new and useful Improvements in Ice-Cream Cabinets, of which the following is a specification.

My invention relates to new and useful 10 improvements in ice cream cabinets, and has for its main object the provision of an un-leakable ice cream cabinet.

Another object is the provision of such a 15 cabinet with means for continuous fresh air ventilation for its hollow walls, and the provision of drainage means for said ventilating means.

Another object is the provision of a cabinet which is simple and durable in construction, highly efficient in use and economical in manufacture.

The usual cabinets on the market are provided with linings which readily get out of order from continuous packing and stamping of the ice around the ice cream containers in said cabinets, and soon become leaky, as a result thereof. I overcome such objections and defects in construction by constructing my cabinet in such a manner that 30 it will not leak even if the inner lining is cracked or broken.

Other objects will appear hereinafter.

The invention consists in the combinations and arrangements of parts hereinafter described and claimed.

The invention will be best understood by reference to the accompanying drawings forming a part of this specification, and in which,

40 Fig. 1 is a perspective view of my improved cabinet,

Fig. 2 is a horizontal sectional view of a portion of the side wall, taken along line 2-2 of Fig. 1,

45 Fig. 3 is an elevational view along line 3-3 of Fig. 5, showing the frame work of the walls, the tarred felt between the vertical and lateral members being mostly omitted, for clearness of illustration,

50 Fig. 4 is a fragmentary vertical section of the wall and floor, taken on line 4-4 of Fig. 5, showing the arrangement of the various elements of the wall and floor, and also of the ventilating and draining means,

Fig. 5 is a broken plan view of the cabinet, 55 and

Fig. 6 is a vertical section through the floor, taken on line 6-6 of Fig. 5,

The form of my invention illustrated in the drawings consists of a cabinet comprising two compound side walls 10 and two compound end walls 11, each of which is arranged for ventilation by fresh air; a compound floor 12 composed of a plurality of layers, of various materials; means for ventilating and draining said compound walls; and means for draining the interior space of the cabinet.

The cabinet will be furnished in various sizes and shapes, the medium size being 70 about 21 inches wide, 47 inches long, and 30 inches high. The frame work of the medium sized cabinet comprises four corner posts 14, for which 2 by 4 wood posts are preferably used, and between said corner posts, 75 four floor sills 15 are fastened by means of nails or screws, or in any suitable manner, said sills being preferably 2 by 4 wood posts, laid with the narrow 2 inch side vertical, as shown in Fig. 3. The corner posts extend 80 a few inches below the floor sill to form legs or supports for the cabinet. Upon each floor sill adjacent the outer edge thereof, I erect a series of uprights 16 preferably 1 by 2 inches in cross section and spaced 2 inches 85 apart, providing a series of ventilating spaces 17 between said uprights, as shown in Figs. 2 and 3. A layer of tarred felt 18 is placed on the outside of said upright 16 and a layer of wall board 19 is placed exterior of said tarred felt. On the outside of 90 said wall board I place a good quality of finishing board 20, of the usual $\frac{3}{8}$ inch thickness, which is smoothed and polished, and varnished or painted as desired, said 95 finishing board covering the walls from the floor to the top of said cabinet. Said members 18, 19 and 20 form the outer partition or section of the compound wall, as best seen in Fig. 2. An intermediate partition is provided at the inner side of the uprights 16 and the air spaces 17, which comprises an upper board or strip 21, an intermediate board 22,

100 and a lower board 23, each being preferably $\frac{3}{8}$ by 4 inches in cross section, and $\frac{3}{8}$ inch cork slabs 24 and 25 fill the spaces between said boards or strips, as indicated at the left hand side in Fig. 3. A layer of tarred 105

felt 26 covers the side of said boards and cork slabs adjacent the space 17, and a similar layer of tarred felt 27 covers the opposite or inner side thereof. Uprights 28 like the uprights 16 are placed inside of the felt 27 of the intermediate partition, and spaced 2 inches apart providing a series of air spaces 29. The lower board 23 and the layers of felt 26 and 27 do not rest upon the sill 15, but extend about $\frac{1}{8}$ of an inch above the sill as shown in Figs. 3 and 4, to provide a space or channel 30, which affords communication between the adjacent ventilating spaces of each series and between the opposite ones of both series of spaces, and also provides communication between the spaces of the several walls, as indicated in Fig. 4.

I provide an inner partition or wall section which comprises a layer of wall board 31 placed adjacent the uprights 28, a layer of tarred felt 32 placed on the inner side of the wall board, and a lining of sheet metal 33 which forms the inner lining of the cabinet.

The floor is a compound one, composed of a plurality of superposed layers of various materials. Several cross beams 35 (see Fig. 6), preferably consisting of 2 by 4 creosoted posts, connect the side sills 15, intermediate the end sills, and beneath the sills and said beams 35 a sheet of metal 36 is fastened forming a bottom layer of the cabinet. Strips of cork 37 are placed between said beams 35, above the metal sheet 36, and floor boards 38 of the usual $\frac{1}{2}$ inch material rest upon said beams and sills. Upon said floor boards, a layer of wall board 39 is placed, thereon a layer of tarred felt 40, and upon the same a lining of sheet metal 41 forming the inner floor lining of the cabinet. Said floor lining 41 is made continuous with the sheet metal lining 33 of the side and end walls, or is soldered or otherwise fixed thereto to form air-tight and water-tight joints.

The means for draining or removing the brine from the cabinet comprises a 1 inch metal pipe 43 laid in the lower inner corner of the cabinet, close to the inner lining. The inner end or intake 44 of the pipe is placed 2 inches above the floor, with the end opening positioned towards the inside of the cabinet, so that 2 inches of cold brine are continuously left in the cabinet to facilitate cooling the same. The pipe extends through the wall and into a 4-way connection 45 which is provided with removable plugs 46 for inspecting and cleaning out the connection and the pipe. Said connection 45 is joined by a short pipe 47 with a similar 4-way connection 48 provided with a plug 49, and connected to a depending pipe 50 which leads to the sewer. The end towards the cabinet of the connection 48 is joined to the ventilating mechanism.

In addition to the air spaces within the walls of the cabinet, as previously described, I provide means for supplying fresh air to said wall spaces in order to properly ventilate said walls, said means being furthermore arranged to also drain moisture from said walls, and especially from the inner spaces of the walls, which moisture may have leaked into the walls through a rupture of the inner metallic lining of the cabinet. Said ventilating means comprises a passage 51 extending from the air spaces 17 and 29 and the channel 30, and leading into the 4-way connection 52, fastened to the lower end of the floor. Said connection 52 is provided with clean-out plugs 53, and is connected to a 3-way valve case 54 of any suitable construction, which is in turn connected to said 4-way connection 48 and through it to the sewer, thus providing means for draining the walls of the cabinet. The valve 54 is provided with a fresh air inlet or opening 55 at the upper end, and with a valve handle 56 for controlling said valve, and whereby the passage 51 and the connection 52 may be set to communicate with either the opening 55 or with the drain connection 48 alone, or with both of them, or may be closed from both the connection 48 and the opening 55.

The upper end of the walls is provided with suitable top strips 58, and the outside horizontal and vertical edges of the cabinet may be provided with suitable trimmings 59 and 60, respectively, of metal or of durable wood. A ledge or depression 61 is also provided around the inner edge of the top for receiving a suitable cover (not shown) for the cabinet, such cover being preferably constructed of material and in a manner similar to the floor previously described.

It will be observed from the above description and from the drawings, that the layers of tarred felt are placed on the inner side of each partition to prevent moisture from getting into contact with the layers of wall board and of wood, and placed in said partitions, where the moisture is more apt to leak through to the next partition or section. This construction thus makes the inner face of each wall and section substantially impervious, and in fact makes three walls, each of which presents an impervious face toward the inside of the cabinet. It will also be observed that continuous ventilation by means of fresh air is provided for the walls of the cabinet by means of the valve 54, and the air inlet 55, and that said ventilation may be intermittent by placing the inlet 55 in communication with the 4-way connection 52 and therethrough with the air passage 51 and that said connection may be closed entirely if desired. It is also evident that the 3-way

valve 54 may be set to provide ventilation for the spaces in the walls and simultaneously to provide drainage means for the walls by way of the passage 51, the connection 52, the valve 54, and the 4-way connection 48.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

20. 1. An ice cream cabinet provided with compound walls and an inner metallic lining, said compound walls each including an inner section consisting of a layer of non-conducting material and a layer of impervious material at the inward side thereof; and means to provide a drainage passage for leakage through said lining and said inner section.

30. 2. An ice cream cabinet comprising walls having a plurality of series of ventilating spaces; a partition between said series of spaces; and a channel in said partition joining said spaces and connecting with an outlet to form a drainage passage.

35. 3. An ice cream cabinet comprising walls having a plurality of vertical ventilating spaces; a partition intermediate said spaces; and means at the lower portion of said partition to connect said spaces and to provide a drainage passage for moisture within said wall.

45. 4. An ice cream cabinet comprising walls having a plurality of series of vertical ventilating spaces; a partition intermediate said spaces; and a channel at the lower end of said partition providing means to connect said series of ventilating spaces and to provide a drainage passage for moisture within said wall.

50. 5. An ice cream cabinet having compound walls comprising a plurality of separated sections, one of said sections including strips of cork and layers of felt covering the sides of said cork and section; and ventilating spaces between said sections.

60. 6. An ice cream cabinet having compound walls comprising a plurality of separated uprights; air spaces between the consecutive uprights; and means for providing fresh air to all of said spaces.

65. 7. An ice cream cabinet having compound walls; each wall comprising an inner and an outer and an intermediate section; a series of uprights between each of said sections; air spaces between said uprights; and

a continuous channel located beneath all of said intermediate sections, connecting the adjacent spaces of the same series and also the spaces of the opposite series.

8. An ice cream cabinet having compound walls each wall comprising inner, outer and intermediate sections; a series of uprights between each of said sections; air spaces between said uprights; a continuous channel connecting all the air spaces of the several walls; and means for admitting fresh air to said channel spaces.

9. An ice cream cabinet having walls composed of a plurality of parallel sections; a series of air spaces between each of the consecutive sections; and a layer of impervious material on the inward face of each section to protect each side of said series of ventilating spaces from the entrance of moisture.

10. An ice cream cabinet provided with walls comprising a metallic lining, tarred felt, wall board, cork slabs and a wooden frame work.

11. An ice cream cabinet having walls provided with a plurality of spaced sections; the inner sections of said walls comprising each a metallic lining, a layer of impervious material, and a layer of rigid material; the intermediate sections of said walls comprising porous material, and being provided with a layer of impervious material on each side; and the outer sections comprising each a layer of impervious material; a layer of rigid material and a layer of finishing material.

12. A cabinet having compound walls provided with spaced sections; and a compound floor comprising a metallic lining, a layer of impervious material, a layer of rigid material, a layer of porous material, and an outer sheet of covering material.

13. A cabinet having solid compound walls provided with a plurality of sections and spaces therebetween; and a compound floor comprising in succession a metallic top lining, a layer of impervious material, a layer of wall board, a layer of cork and an outer covering of sheet metal.

14. A cabinet having walls provided with means for ventilating their interiors; means for conducting fresh air to the interiors of said walls; and a control valve with an air inlet connected to said conducting means.

15. A cabinet having walls provided with ventilating spaces; a passage connecting said spaces; a conduit connected to said passage; and means, including a 3-way valve and an air inlet, for ventilating and for draining said walls.

16. A cabinet having walls arranged for ventilation; means for draining the inside of said cabinet; and means connected to said drainage means for draining the interior of said walls.

17. A cabinet having walls arranged for ventilation; means for draining the inside of said cabinet; and means connected to said drainage means for draining and for 5 ventilating the interior of said walls.

18. A cabinet having walls arranged for ventilation; means for draining the interior of said cabinet, said means including a pipe laid adjacent the inner corners of said cabinet, having an inlet opening raised from 10 the floor, and having communication with

an exterior conduit and means for ventilating the interior of said walls and for draining moisture from said walls into said conduit.

15

In testimony whereof I have signed my name to this specification in the presence of two subscribing witnesses.
